APPARATUS FOR DETERMINING THE MOISTURE CONTENT OF INSULATED BOOTS AND SIMILAR ARTICLES

Dwight W. Batteau, Cambridge, Mass., assignor to Flown Corporation, Arlington, Mass., a corporation of Massachusetts

Filed Aug. 28, 1959, Ser. No. 836,723

2 Claims. (Cl. 324—61)

This invention relates to apparatus for measuring the moisture content of articles of irregular shape and more particularly to novel apparatus for supporting the articles to be tested.

In its illustrated form, the present invention is designed specifically to test winter footwear such as infantrymen's combat boots, but it may be adapted to determine the moisture content of other articles as well.

It has been determined that the thermal insulating property of winter footwear of the type having a fleece lining sandwiched and hermetically sealed between inner and outer layers of rubber or other flexible impervious material is materially affected by the moisture content of the lining. So long as the moisture content of the lining is below a certain level, the boot or shoe will provide satisfactory insulation against frostbite at relatively low temperatures. However, when the moisture content exceeds that level, there is a marked decrease in insulating power and frostbite will occur much more readily.

This phenomenon being known, it is very important that each insulated boot be measured for moisture content and that only those boots having less than the maximum permissible moisture content be released for use. Heretofore, however, there has been lacking a device or method capable of reliably and rapidly determining the moisture content of an insulated boot without penetration or at least partial destruction of the boot under test. Prior non-destructive methods and devices have failed to give consistent results on repeated tests of the same boot.

Accordingly, the object of this invention is to provide a novel method and apparatus for rapidly determining the moisture content of insulated winter footwear and similar articles without injury thereto.

Other objects and many of the attendant advantages of this invention will be readily appreciated as the invention becomes better understood by reference to the following detailed description when considered in connection with the accompanying drawings, wherein:

FIG. 1 is a block diagram of a moisture-measuring system constructed according to the present invention;

FIG. 2 is a circuit diagram of the Wheatstone bridge forming part of the system of FIG. 1;

FIG. 3 is a perspective view of a preferred embodiment of the present invention;

FIG. 4 relates to the same apparatus as FIG. 3 and is a vertical section taken along line 4—4 of FIG. 5; and

FIG. 5 is a vertical section taken along line 5—5 of FIG. 4.

The present invention provides a measure of the moisture content in a boot without penetrating or destroying it, by measuring the total change in the dielectric factor of a capacitor containing the boot. The dielectric constant of water at 20° and low frequencies is 80, compared to 1.0 for a vacuum, 1.0003 for air, and approximately 2.6 for rubber. Thus, a small quantity of water introduced into a capacitor can cause a large change in its capacitance. Since the change in total capacitance caused by water is proportional to the quantity of water, measurement of capacitance change resulting from the water alone can be utilized to provide a measure of water content.

Application of this principle to an insulated rubber

2

boot can be effected by placing the boot between the plates of a capacitor. When this is done, the dielectric factor of the capacitor is increased by an amount depending not only on the moisture content but also on the amounts of the other materials, i.e., the rubber and wool, their dielectric constant, and their locations. For a given style of boot, the total amount of rubber and wool varies according to boot size and will even vary in boots of the same size. However, since the dielectric constants of dry rubber and dry wool are relatively small, the changes in total capacitance resulting from variations in sizes of the boots are relatively small compared to the changes produced by even small changes in water content.

Thus, the effect of water is easily separated from the effect of the dry rubber and wool. The change in capacitance due to relative locations of materials is standardized by the boot shape which remains substantially constant for a given style of boot. However, since a boot is of irregular shape, its orientation relative to the plates of the capacitor will also effect the total capacitance, and significant changes in total capacitance will result by merely changing the position of the boot. For this reason, it has been found necessary to provide a capacitor whose geometry is particularly adapted to minimize the effect of orientation of the boot.

FIG. 1 is a block diagram of a complete system embodying the present invention. The system may be broken down as follows: an oscillator 2, a Wheatstone bridge 4, and a detector 6 comprising an amplifier 8, 10 a rectifier 10 and an output meter 12; and as an optional feature, a light indicator 14.

In this case, the oscillator is a Colpitts oscillator producing a 1 kc. output. As shown in FIG. 2, the Wheatstone bridge 4 comprises four series-connected resistors R1, R2, R3, and R4, a variable capacitor C2 connected across resistor R2, and a specially designed boot-holding capacitor C4 connected across resistor R4. Capacitor C2 is of the type having a calibrated dial. The boot-holding capacitor is illustrated in FIGURES 3-5 and is described in detail hereafter.

The output of oscillator 2 is applied to the bridge at points a and c. Detector 6 is across points b and d.

When the voltage drop from point (a) to point (b) is the same as from point (a) to point (d), no current will flow through the amplifier, and the meter will read zero. The following equations represent the two conditions which must be obtained if no current is to flow in the detector:

$$R_1 = \frac{R_3}{R_2} \quad \text{and} \quad R_1 C_2 = R_3 C_4$$

R₁ and R₃ are fixed, thereby enabling the following mathematical statements:

$$C_4 = k C_2 \quad \text{and} \quad R_4 = K R_2$$

where k and K are simply constants of proportionality. Since the problem is to ascertain boot-holding capacitor C4, it is sufficient to adjust R2 and C2 until the bridge is balanced and then observe the value of C2 as indicated on its calibrated dial.

Since the value of C2 is a function of the water content of the boot under test, the dial of C2 may be calibrated directly in terms of water content or the amount of water in the boot under test may be determined by a 65 calibration curve which compares variations in value of C2 with water content. Separate calibration curves may be set up for different types of boots.

The full wave rectifier circuit 10 is connected across the amplifier load circuit and provides direct current for 70 the meter 12. When the meter reads zero, the bridge is balanced and the value of C2 indicates the water content.

For production testing, an indicator light 14 can be coupled to the bridge so as to go on at a selected position of C2. This selected position may be the one obtained when balancing the bridge for a standard boot, i.e., a boot whose water content is known and is at or just below the maximum or threshold value. Thus, in testing for a boot, the operator need not read the dial but need only observe whether a light is turned on when the meter needle reads zero.

It has been determined that in order for the system to be accurate with minimal operator skill and with no significant deviation in result due to orientation of the boot, the capacitor C4 should be spherical, made up of one ball within another, with the two balls in substantially symmetrical-spaced relationship. This construction has the advantage that in use the inner ball is inside the boot, providing support and facilitating location of each boot in a standard position. The effect of orientation of the boot is minimized because a given amount of material will produce the same effect so long as it is the same distance from the surfaces, regardless of angular location.

FIGS. 3-5 illustrate the spherical capacitor of the present invention. FIGS. 3-5 show a housing 20 made up of a bottom wall 24, a top wall 26, and side walls 28. The casing is supported by suitable legs 30 attached to bottom wall 24.

Top wall 26 is formed with a circular opening in which is secured a large bottom hemisphere 32. The marginal portion or mouth of hemisphere 32 projects above top wall 26 and is flared as at 34. The hemisphere may be supported solely by its marginal portion acting on top wall 26; or, if desired, screws 37 may be driven through the hemisphere laterally into top wall 26.

Hemisphere 32 has an opening at its bottom in which is secured a coaxial connector 36. Coaxial connector 36 supports a long brass rod 38 which extends radially of the hemisphere. Surrounding brass rod 38 and attached to hemisphere 32 by screws 40 is a hollow post 42 formed of plastic. Post 42 has a plurality of thin sector-shaped webs 44. One of the webs 44a is wider than the rest. The top end of post 42 has a concave depression 46. Seated on the concave surface 46 is a smaller hemisphere 50 whose mouth has a flared rim 52. Hemisphere 50 is secured to post 42 by a short post 56. The bottom end of post 56 extends through a hole in hemisphere 50 and is provided with external threads 58 which are screwed into a tapped hole provided in the top end of post 42. Secured to the top end of post 56 by means of a screw 60 is a small top hemisphere 62. The edge of hemisphere 62 fits within rim 52 of bottom hemisphere 50. Post 56 has a central bore 64 into which extends the upper end of rod 38. Post 56 also has a lateral opening in which is mounted a set screw 66. Set screw 66 engages rod 38 and operates to electrically couple post 56 and hemisphere 50 and 62 to the brass rod. The brass rod 38 and bottom hemisphere 32 are coupled by coaxial connector 36, a cable 68, and another coaxial connector 70 to appropriate points in an instrument housed in a case 74 and embodying the system of FIGS. 1 and 2.

Attached to the top wall 26 of the case 20 are two bearing blocks 80 and 82 which rotatably support a shaft 84. Shaft 84 is secured to a bracket 86 which is formed integral with a top hemisphere 88. Attached to shaft 84 at the opposite ends thereof are two arms 90 and 92,

which extend into case 20 through slots 94. The upper ends of these arms are provided with suitable grips 96. Arms 90 and 92 are bent at a point located below shaft 84 and their bottom ends are connected to each other by a cross bar 98. The latter carries a counter weight member 100. Arms 90 and 92 are bent at an angle such that when the hemisphere 88 is pivoted to open position as shown in each of the figures, the counter weight will be at its lowest position and will act to hold the hemisphere open.

The four hemispheres and the connecting post 56 are all constructed of aluminum. The outer hemispheres have an anodized finish. The center post 42 may be formed of any suitable plastic, preferably polystyrene or methylmethacrylate polymer.

As shown in dotted outline in FIG. 4, a boot to be tested is placed over the inner sphere and post 42 and is positioned with the toe of the boot located directly above web 44a. Web 44a serves as a positioning guide so that each boot will automatically assume the same angular position and also to support and hold open the expansion pleat on the front of the upper part of each boot.

With the boot in place, the top hemisphere is closed by manipulation of arms 90 and 92 and the instrument operated to determine its moisture content.

Obviously, many modifications and variations of the invention are possible in the light of the above teachings. It is to be understood, therefore, that the invention is not limited in its application to the details of construction and arrangement of parts specifically described or illustrated, and that within the scope of the appended claims, it may be practised otherwise than as specifically described or illustrated.

I claim:

1. Apparatus for measuring the relative water content of articles by measuring their relative capacitance, said apparatus having in combination; a base; a capacitor mounted on said base having a first and second electrode in electrically insulated relation, said first electrode being substantially spherical in configuration, said second electrode being hollow and at least in part spherical and arranged around and concentrically with said first electrode; said electrodes being spaced apart to receive said articles, whereby the capacitance of said articles placed between said electrodes is added to the fixed capacitance between said electrodes and distortions in the combined capacitance of said electrodes and said articles due to variations in the position of said articles are minimized; means including a balanced bridge circuit for measuring an unknown capacitance; and said capacitor connected to said measuring means in the position of the said unknown capacitance.

2. The apparatus defined in claim 1, further characterized by said first electrode constructed and arranged with respect to a said article having a relatively hollow configuration to fit therein and support the same with said article substantially surrounding said first electrode, whereby the said article influences the dielectric field of said capacitor substantially to its maximum extent.
